United States Patent Office.

HENRY L. BOWERS, OF HARRISBURG, PENNSYLVANIA.

Letters Patent No. 100,006, dated February 22, 1870.

IMPROVEMENT IN CELLAR-HOIST OR ELEVATOR.

The Schedule referred to in these Letters Patent and making part of the same.

To all whom it may concern:

Be it known that I, HENRY L. BOWERS, of the city of Harrisburg, in the county of Dauphin, and State of Pennsylvania, have invented a new and useful improvement, consisting of a "Cellar-Hoist or Elevator" and "Cellar Stairs or Steps" combined.

The construction of the same, and manner of combination and arrangement, I will proceed to describe.

The drawing represents a perspective view of the device in position for operation.

The essential feature of novelty in this invention consists in providing a compact, convenient, and powerful hoisting machine, that will always be ready for use, and combining the same with cellar stairs or steps, substantially as follows:

The uprights or side supports B B' of the stairs are made of timber sufficiently strong for the purpose. They are given a proper degree of inclination from a vertical position, and rest upon a proper foundation, their upper ends being securely fastened to the sill D.

The said pieces B B' have their front edges grooved or channeled out, as seen at u u in the drawing. These grooves are intended to act as a guide-way for the hoisting table A.

Said table is made substantially as shown in the drawing.

That portion of the frame-work of the table A that bears against the pieces B B' has tongues formed upon it to enter into and slide easily in the grooves in said pieces when in position, thus retaining and guiding the table when it is hoisted or lowered.

Upon each side of the frame of table A, at a point, s, ropes or chains b b are rigidly secured by their ends. Said ropes or chains are carried up over the grooved wheels n n. These wheels are secured to the outside surfaces of the pieces B B', and near their upper ends, in such a manner as to permit them to turn freely upon the studs or bolts that secure them in place.

The ropes or chains b b are made fast to the barrel shaft e of the winch or crane-gear. Said winch or hoisting gear is constructed substantially as is shown in the drawing, and consists of a barrel shaft, e, and driving shaft d, that are supported by suitable hangers.

Upon one end of the shaft e a large gear-wheel, o, is secured. A small pinion, r, that is fastened to the driving shaft d, meshes into the wheel o, as is shown.

Upon the opposite end of the shaft d a crank, e, is secured.

A ratchet-wheel, i, in which the click or pawl p catches, is also fastened in place upon the shaft d, immediately in the rear of the crank e.

The supporting hangers are connected so that the entire winch is in a compact and portable form. It is bolted or otherwise properly secured to the joists or other suitable timbers in the cellar, overhead, so that the handle of the crank e is accessible from the floor. The position given the said winch should be directly opposite to or in a straight line in the rear of the cellar stairs, so that the ropes b b will train in a correct manner.

The steps a a a, &c., should be set back a short distance from the front edge of the uprights B B', so as to permit the table A to pass their front edges readily.

The uprights B B' should have their lower ends let into the bottom of the cellar up to the dotted line E F. The lower portion or frame-work of the table A should also be sunk a similar depth, a proper excavation being made to permit the same. This should be walled or planked upon its sides, so as to prevent dirt from falling in and obstructing the table.

This plan of construction will bring the top of the table A on a line with the bottom of the cellar. In fact, if it is floored, the table will form a portion of the floor.

In using this device, weighty articles can be placed upon the table with great ease, either for elevating them from the cellar floor to the street, or for lowering them from the street into the cellar.

By the operation of the winch C, the hoisting and lowering is rendered easy and secure, as the ratchet-wheel acts as a guard to prevent slipping, and enables the operator to arrest the ascent or descent of the article at any point desired.

The frame-work of the hoisting table A may be provided with small wheels or rollers, with flanges, to run upon the front faces of the uprights B B'. The grooves in the faces of the uprights can then be dispensed with, as well as the tongues upon the frame.

I do not desire to claim broadly the general application of a winch to an elevator, as I am aware that it has been so applied; but

What I do claim as new, of my invention, and desire to secure by Letters Patent of the United States, is—

The peculiar combination and arrangement of the elevating table A, stair uprights B B', and winch C, the whole constructed and operating substantially as herein set forth.

HENRY L. BOWERS. [L. S.]
